UNITED STATES PATENT OFFICE

HERBERT W. ORNDOFF, OF NEW ORLEANS, LOUISIANA, ASSIGNOR TO THE E. V. BEN-JAMIN CO., INC., OF NEW ORLEANS, LOUISIANA, A CORPORATION OF LOUISIANA

GRIPPING DEVICE

Application filed June 18, 1928. Serial No. 286,386.

This invention relates to improvements in gripping devices, and more particularly concerns such devices for employment in removing a sheet from a printing cylinder.

5 The invention is illustrated in connection with a sheet handling machine in which a length of material is assumed to be cut into equal lengths, delivered to a printing press, removed therefrom and folded for further 10 operation. In the specific illustration, it is shown as applied to a bag printing and folding machine of the type set forth in the Goben Patent 1,482,605 of Feb. 5, 1924.

In such a machine, the cut lengths of cloth 15 or other material are delivered to a printing cylinder of large diameter on which they are imprinted and from which they are removed by a receiving drum which in the illustrated form delivers them to a discharging drum for folding. The receiving drum is usually made about one-half the diameter of the printing cylinder, and as it is driven at the same peripheral speed, it makes two revolutions to one revolution of the printing 20 cylinder. The gripping fingers must extend beyond the periphery of the receiving drum in the gripping position: and hence it has heretofore been customary to provide a recess half way around the printing cylinder 25 from the position of the edge of the cloth or other material being printed, to permit the passage of the gripper fingers, without entering the path of the cylinder.

According to the present invention, the actuating member for the gripper fingers on 30 the receiving drum is caused to operate differently upon the gripping devices at the time when the gripper fingers come opposite the printing cylinder, accordingly as the bag 35 is to be seized or not.

In the accompanying drawings:

Figure 1 is a sectional end view of the operative parts substantially on line 1—1 of 40 Fig. 2.

Fig. 2 is a top plan view of one end of the machine.

Figs. 3 and 4 are sectional end views on a larger scale than that of Figs. 1 and 2, substantially on lines 3—3 and 4—4 of Fig. 2,

respectively, but with parts omitted for greater clearness.

In these figures, the lengths of bag material are delivered to the printing cylinder 19 in any suitable manner, and as the cylinder turns about its axis 17, the bags are printed and the advancing edge comes opposite the receiving drum 31 (Fig. 1) for engagement by gripping devices mounted on this receiving drum 31. These gripping devices remove the bag material from the printing cylinder 19 and carry it over to engagement with the discharging drum 81 moving on an axis 80, from which it is finally discharged from the machine, usually with a simple fold to form the bag ready for sewing. The diameter of the printing cylinder 19 is about twice that of the receiving drum 31, and the latter is caused to make two revolutions for one of the cylinder 19. 70

It is preferred to form the receiving drum 31 as a plurality of spaced disks 32 (Fig. 3) fastened to a common shaft 30 by set screws 33. These disks are usually formed with spider arms 33 for greater lightness. The 75 disks are provided with the arcuate slots 36 to receive the common shaft 56 of the gripper devices. This shaft is journaled on the rock arm 47 for each disk mounted on the shaft 30, so that it may be swung around to locate 80 the gripper shaft 56 at various points in the arcuate slot 36 with respect to the folding blade 41, according to the widths or lengths of the bags to be folded. The arm 47 is likewise provided with a plate 52 having apertures for a locating pin 54 and a securing screw 53, and being provided adjacent the periphery of the disk 32 with a gripping plate 55 to cooperate with the gripping finger 60 proper, which is fixedly secured to the 90 roller gripping shaft 56 by a set screw 61.

At the end of the shaft 30 is secured a control disk 31^a in which the shaft 56 is journaled. This shaft 56 carries at the end outside the control disk 31^a a lever arm 68 having at one end a roller 70 and at the other end a pivot 72, whereby it is connected to the link 74 which is guided in an eye 34 on the disk 31^a. The spring 75 reacts between a collar 74^a on the rod 74 and the eye 34 to 100

force downward on the rod 74 in the position of Fig. 4, and thereby constantly tends to rock the shaft 56 and its lever 68 in a clockwise direction.

During each revolution of the shaft 30 with its receiving disks 32 and control disk 31^a, the roller 70 is brought into contact with a stationary cam 64 fastened by the feet 64^a to the side standard 10 of the machine (Fig. 2). As a result of this engagement, the roller 70 is forced outward or in a counterclockwise direction with respect to the axis of shaft 56, against the spring 75, thus rocking the shaft 56 to cause the gripper finger 60 of the respective disks 32 to be opened to the position shown in Fig. 3. When the roller 70 leaves the surface of the stationary cam 64, it is permitted to rock inward under the action of the returning spring 75 until the gripper fingers 60 are again closed against the respective plates 55, and if a bag has been brought between the gripper fingers and the plates by the printing cylinder 19, this edge of the bag is engaged and the bag is drawn over onto and along with the receiving drum 31.

The cam 64 is composed of two parts, one remaining absolutely fixed with respect to the standard 10 and the other being adapted to move toward and from the standard but being stationary with respect to the shaft 30. This latter extension or portion 65 of the cam 64 is carried fixedly on a lever 66 which is pivoted on a cap screw 67 carried in a foot member 69 of the framework 10; and at the other end of the lever is pivotally mounted a roller 90 having its axis of rotation radially directed with respect to the shaft 17 of the printing cylinder 19. The printing cylinder is provided on its end with a cam 91 fixed thereto. This cam is located substantially opposite the point of the printing cylinder at which is located the advancing edge of the bag being printed, being located on the printing cylinder so that the roller 90 is engaged by the cam 91 just before the roller 70 comes to the end of the fixed portion of the cam 64 (e. g., when the roller 70 is at the position 70^a in Fig. 1). The roller 90 causes the lever 66 to rock in a clockwise direction in Fig. 2, and to bring the cam extension 65 into the same plane as the fixed portion of the cam 64, so that the roller 70 will now travel over the full extent of the cam 64 and its extension 65, and thereby cause the roller 70 to open the gripper finger 60 for the reception of the printed bag. As soon as the roller 70 reaches the position 70^b (Fig. 1) it passes from the cam surface respectively toward the axis 30, so that the gripper fingers are closed upon the edge of the bag and the latter is drawn around with the receiving drum.

As soon as the roller 90 leaves the cam 91 during the movement of the latter beneath it, the lever 66 is rocked in a counterclockwise

direction by the returning spring 83 fastened to an adjustable arm 84 secured to a suitable point of the standard 10. The cam 64 and the cam extension 65 are formed with beveled edges so that the two parts are held in the same plane when actuated by the roller 90; and are likewise provided with interlocking members 64^x to prevent a relative upward movement of the cam extension 65 under the pressure of the roller 70.

In operation, a bag is printed on the printing cylinder, and during the rotation of this cylinder, the cam 91 is caused to rock the roller 90 in a clockwise direction in Fig. 2, so that the cam extension 65 provides a full length track for the roller 70 when the advancing edge of the bag material comes opposite the receiving drum, thereby opening the gripping fingers 60 so that the bag material enters beneath the gripping fingers; and upon the passage of the roller 70 from the end of the cam surface on the cam extension 65, the gripping fingers 60 are moved downward to pinch the advancing edge of the bag material against the gripping plates 55 of the respective disks 32 along the length of the printing cylinder 19. The bag is thus removed from the printing cylinder 19. When the receiving drum has completed one rotation, the printing cylinder has only completed a half rotation, but at this time, the lever 66 has already been rocked in a counterclockwise direction in Fig. 2 so that the cam extension 65 is no longer in alignment with the fixed portion 64, since there is no cam strap 91 on the printing cylinder 19 to move the roller 90. The roller 70 of the control disk 31^a therefore does not come in contact with the cam extension 65, but moves radially inward after leaving the vertical edge of the fixed cam 64 and attains a position such as illustrated at 70^c in Fig. 1, the gripping fingers then remaining depressed or in engagement with the gripping plates 55 during this passage opposite the printing cylinder 19, so that the printing plate may be permitted to extend substantially throughout the entire periphery of the printing cylinder 19, and without the necessity of providing a groove in the printing cylinder for the passage of the fingers 60 at a point diametrically opposite the advancing edge of the bag material being printed.

It will be understood that in the illustrated form, the receiving drum is caused to engage the bag material substantially midway of its length by the folding blades 41 held at the peripheries of the respective disks 32 by the plates 40 and securing screws 42. The position of the gripping fingers 60 and gripping plates 55 with respect to the folding blades 41 is adjusted by loosening the set screws 46 and 31^x and rotating the arms 47 and control disks 31^a relatively with respect to the receiving disks 32 and shaft 30 until the peripheral dis-

tance of the gripping plate 55 from the folding blades 41 is about equal to the width of the finished bag; whereupon the screws 46 and 31^x are again tightened to hold the control disk, arms 47 and the receiving disks 32 rigidly together.

Any desired means may be employed for causing the printing cylinder and the receiving and discharging drums 31 and 81 to rotate at the proper and respective peripheral velocities, conventionally shown as gears 85, 115 and 116.

It is obvious that the invention is broadly applicable in the art, and that it is not limited 15 in its application to the specific example shown.

What I claim as new and desire to secure by Letters Patent is:

1. In a sheet handling machine having a 20 cylinder and a receiving drum with driving means therefor, said drum being driven at a greater rotational speed than said cylinder, a gripping device carried by said drum and adapted to seize a sheet on said cylinder, 25 said gripping device having a shaft, a gripping finger and a rock lever with a cam-engaging member fixed to said shaft, a cam lever, a cam mounted on said cam lever to rock into and out of the path of movement 30 of said cam-engaging member, and means on the cylinder cooperating with said cam lever to rock said cam lever and cam to a position in which the cam-engaging member is moved by said cam to present said finger for seizing 35 a sheet on the cylinder.

2. In a sheet handling machine having a cylinder and a receiving drum with driving means therefor, said drum being driven at a greater rotational speed than said cylinder, 40 a gripping device carried by said drum and adapted to seize a sheet on said cylinder, said gripping device having a shaft, a gripping finger and a rock lever with a cam-engaging member fixed to said shaft, a cam lever, a cam mounted on said cam lever to rock into and out of the path of movement of said cam-engaging member, means to normally retract 45 said cam out of the position in which it is in alignment with said cam engaging member, and means on the cylinder cooperating with 50 said cam lever to rock said cam lever and cam to a position in which the cam-engaging member is moved by said cam to present said finger for seizing a sheet on the cylinder.

3. In a sheet handling machine having a cylinder and a receiving drum with driving means therefor, said drum being driven at a greater rotational speed than said cylinder, a gripping device carried by said drum and adapted to seize a sheet on said cylinder, a relatively stationary cam to open said device ready for seizing the sheet, a cam extension adapted in one position to hold said device in seized condition when opposite the cylinder, cooperating elements on said cam

and said extension to align and prevent movement of said extension when presented in continuation of said fixed cam, and means on said cylinder cooperating with said cam extension to move the same into a position in continuation of said cam.

4. In a bag printing machine having a cylinder and a receiving drum with driving means to move said drum by a plurality of revolutions for each revolution of said cylinder, said receiving drum having a rock shaft thereon, gripping fingers fixed to said rock shaft and movable therewith, a cam, a cam extension, said fingers in one position being outside of the path of the cylinder periphery, and in a second position in the path of such periphery to seize a bag blank on the cylinder, a roller eccentrically mounted on the rock shaft to cooperate with the cam and extension to open said gripping fingers and hold them in said second position, a cam lever pivoted on the machine frame to present said cam extension in continuation of said cam or remove it therefrom, and a cam on said cylinder engaging said lever to move 90 said cam extension into continuation of said fixed cam whereby to hold the fingers in said second position when a bag blank is to be seized.

5. In a sheet handling machine having a cylinder and receiving drum with parallel axes and driving means therefor, said drum being driven at a greater rotational speed than said cylinder, gripping devices carried by said drum and adapted to seize a sheet 100 on said cylinder, operating means for said gripping devices, a cam lever mounted on a fixed pivot whose axis is substantially at right angles to said axes, a cam secured to said lever to rock into a position in which it is engaged by said operating means and a position in which it is free of said operating means, and a cam moving with said cylinder to rock said lever, whereby the said devices are opened ready for seizing a sheet in one 110 of said positions and are retained closed in the other of said positions.

6. In a sheet handling machine having a cylinder and receiving drum with parallel axes and driving means therefor, said drum being driven at a greater rotational speed than said cylinder, a gripping device carried by said drum and adapted to seize a sheet 115 on said cylinder, operating means for said gripping device, a fixed cam member adapted to cooperate with said operating means to open said gripping device ready for seizing a sheet on said drum, a cam lever, a movable cam member secured to said lever and adapted to rock therewith into a position in 120 extension of said fixed cam in which it engages said operating means to hold said device open and then to release it for seizing the sheet on the cylinder, and into a position in which it is disengaged from said fixed 130

cam, whereby said operating means will cause said gripping device to be returned to closed position free of engagement with said drum, and means to move said lever and movable cam from one of said positions to the other.

5 In testimony whereof, I affix my signature.

H. W. ORNDOFF.
